UNITED STATES PATENT OFFICE.

JULIUS KÖSTER, OF ZITTAU, GERMANY.

WATER-TUBE STEAM-GENERATOR.

SPECIFICATION forming part of Letters Patent No. 769,547, dated September 6, 1904.

Application filed June 13, 1904. Serial No. 212,370. (No model.)

To all whom it may concern:

Be it known that I, JULIUS KÖSTER, a subject of the King of Saxony, and a resident of Zittau, Germany, (whose post-office address is No. 5^b Bahnhofstrasse, Zittau, Saxony, German Empire,) have invented new and useful Improvements in Water-Tube Steam-Generators, of which the following is a specification.

- 10 The present invention relates to steam-generators with erect water-tubes which are so connected one with the other that the water is supplied to all of them from below and the steam led off from above.
- 15 The improvement chiefly consists in each of the water-tubes being divided into several compartments or chambers and in special devices being arranged in each of these compartments for promoting the circulation of the water-tube.

20 The invention is illustrated on the here-annexed drawings, of which—

Figure 1 represents a cross-section of the generator on the line 1 1 of Fig. 3; Fig. 2, a longitudinal section on line 2 2 of Fig. 3; Fig. 25 3, a horizontal section; Fig. 4, a longitudinal section of one of the water-tubes, in enlarged scale.

Each water-tube A, Fig. 4, is divided by 30 partitions *a b* into separate compartments *c d e*. These partitions, however, do not fit tightly against the wall of the tube A, but leave an interval of sufficient size to allow so much water to pass upward as is requisite to compensate for the water converted into steam. Within the compartments and coaxial therewith are located tubes *f g h*, open at both ends, which serve for promoting the circulation of the water. The lowermost of the circulation- 35 tubes may be secured to the water-tube by angle-irons and rivets and the partition-walls and the other circulation-tubes may be built up on the lowermost tube in the same way, as this is clearly shown in Fig. 4 of the drawings.

The combustion-chamber of the furnace is provided with substantially horizontal walls or partitions *m n*, of refractory material,

through which pass the described water-tubes, the position of said refractory partitions *m n* corresponding to that of the partitions within the water-tubes. Said partitions, which are provided with openings at alternate ends, determine the course of the heating-gases proceeding from the adjacent grate, as marked by arrow in Fig. 2. The gases first pass along the upper portion *i* of the water-tubes corresponding to the uppermost compartment. Then they pass downward and backward, thus sweeping over the surfaces *k* of the water-tubes corresponding to the next lower compartment, and so on, according to the number of compartments in each water-tube. The gases thus pass along the outer surfaces of the water-tubes in a direction opposite to that in which flows the water within the tubes. On account of the fact that in each of the compartments into which the water-tubes are divided the water between the wall of the water-tube and that of the internal circulation-tube is heated, whereas to the water within said circulation-tube no heat is directly supplied, there arises a state of circulation in which the water between the water-tube and the circulation-tube rises and then descends within said circulation-tube, after which it rises again, as before.

o is the pipe by which all the water-tubes are supplied with water by pipes *p*. The steam is led off from the upper portion of the water-tubes by pipes *r* to the common steam-pipe *s*.

t is a pipe connecting the common steam-pipe with the water-supply pipe *o*, in which pipe *t* may be arranged the water-gage.

What I claim, and desire to secure by Letters Patent of the United States of America, is—

1. In water-tube steam-generators the combination with the water-tubes of partitions, dividing the water-tubes in several compartments, and circulation-tube in each of these compartments, substantially as and for the purpose stated.

2. In water-tube steam-generators the combination with the water-tubes of partitions,

dividing the water-tubes in several compartments, circulation-tube in each of these compartments, combustion-chamber and horizontal walls dividing the combustion-chamber, 5 compartments corresponding to the compartments into which are divided the water-tubes, substantially as and for the purpose stated.

In testimony whereof I have hereunto set my hand in presence of two subscribing witnesses.

JULIUS KÖSTER.
